UNITED STATES PATENT OFFICE

HARRY ZUBICK, OF NASHUA, NEW HAMPSHIRE

HEEL-SEAT-PREPARING MEANS

Application filed May 4, 1929. Serial No. 360,592.

The invention primarily has for its object to provide a novel means for facilitating the affixing of wooden heels to shoes otherwise built up, and by the employment of which the surplus extension of the out-sole is properly trimmed away, and the heel portions prepared for being received snugly into the heel seat concavity in a manner assuring neat close fitting of the heel edges, by a single hand or power pressed application of the said means.

It is well known that the conventional forms of wooden heels affixed to shoes are provided with concave seats and that the heel portion of the shoe formed by the turned-under upper edges and the out-sole tongue extension fitting the depression left within those edges must be trimmed and pressed to suitable seating shape by more or less laborious and varyingly accurate skiving and tamping. This shaping is customarily accomplished by hand skiving and hammer tamping.

Therefore, in its more detailed nature the invention resides in the provision of a novel die head structure provided with a suitably shaped concavity for shaping the heel portion and which carries novel cutting edges so constructed and disposed that when the said die head is forcibly brought into engagement with the shoe heel portion the out-sole end will be trimmed and the heel portion properly press-shaped in the single operation so that when the heel is applied a neat and snug fit is assured.

Other objects will in part be obvious and in part be pointed out hereinafter.

To the attainment of the aforesaid objects and ends, the invention further resides in the novel details of construction, combination and arrangement of parts, all of which will be first fully described in the following detailed description, then be particularly pointed out in the appended claims, reference being had to the accompanying drawings, in which:—

Figure 1 is a side elevation of a head for forming full-breasted heel seats.

Figure 2 is a front elevation of the head shown in Figure 1.

Figures 3 and 4 are top and inverted plan views respectively of the head shown in Figure 1.

Figure 5 is a perspective view illustrating the head shown in Figure 1 in practical use.

Figure 6 is a perspective view of a shoe showing the heel seat prepared by the head shown in Figure 1.

Figure 7 is a perspective view showing a shoe with its heel affixed but before the pasting down of the finish facing strip end.

Figure 8 is a perspective view of the completed shoe.

Figures 9, 10, 11 and 12 are side, end, top and inverted plan views respectively of a head for forming half-breasted heel seats.

Figure 13 is a perspective view illustrating the head shown in Figures 9—12 in use.

Figure 14 is a perspective view of a shoe ready for the affixing of its half-breasted heel.

Figure 15 is a perspective view illustrating the shoe of Figure 14 completed by the affixing of its heel.

In the drawings 1 designates a shoe support standard forming a part of any suitable die stamping machinery and which carries a shoe mounting head 2 on which a shoe to be operated upon is securely clamped as at 3. The particular type of die press machine upon which the invention is used is immaterial and in fact the die can be manipulated by hand.

The mounting standard 1 is opposed by a die carrying head indicated at 4 and which is provided with a dove-tail grooveway 5 to removably receive the dove-tail mounting head 6 which is secured as at 7 to the die head proper designated 8.

The working face of the die head is concaved as at 9 to engage the shoe heel portion and shape it to provide the desired convex heel seat for fitting the concaved seated portion customarily provided in wooden heels.

The concaved face of the die head 8 is provided with a body recess 10 and two laterally extended recesses 11 to receive the knife plate 12 and its lateral extensions 13 respectively. The plate 12 is removably secured in the recess 10 by securing screws 14.

and the said plate is so shaped as to provide a U-shaped cutting edge 15 including the laterally directed cutting edge extensons 16. The die shown in Figures 1 to 5 may also be used in putting on the Cuban heels.

In the use of the invention the shoe heel upper indicated at 17 is turned over to form a securing flange 18 which is secured over the inner sole in the customary manner illustrated in Figure 7 of the drawing forming a recess 19 which is filled by the tongue extension 20 of the outer sole 21 and breast line shoulders 22 against which the breast line 23 of the heel 24 may abut. It will, of course, be understood that while this cutting action is taking place the concavity of the die head properly shapes the heel portion to fit the concaved seat of the heel. In Figure 6 I have shown a shoe prepared for the affixing of the heel. In Figure 7 I have shown the heel applied to the shoe and in Figure 8 the shoe is shown in its complete form with the facing or finishing strip 25, shown partially applied in Figures 6 and 7, pasted down over the heel breast face to complete the shoe.

In Figures 9 to 15 I have shown a modified form of the invention in which the die is constructed in the same manner as hereinbefore described except that the cutting edges 26 with their lateral portions 27 are formed integrally with the die head body. In this form of the invention the knives may terminate or merge with the body of the die head as indicated at 28 to provide for termination of the cutting action at this point. When the die is so constructed the sole extension may be skived down to a fin at its rearmost edge so that when the die is forced home it will form a tongue of a convex tapering nature such as illustrated in Figure 14 of the drawings, the same breast shoulders for abutting the heel being provided as in the case of the die head hereinbefore described in detail.

It should be understood that that portion of the die embraced within the confines of the knife or cutting edge 15 is located in a deeper plane than the pressing or die face proper 9 of the die head so that the tongue part 20 will not interfere with the application of proper die pressure to the portion 18 of the shoe, see Figure 2.

From the foregoing description I have disclosed a simple construction of die head through the employment of which die head the shoe heel portion may be conditioned for providing a close neat fit between the wooden heel and the said heel portion, the whole accomplishment taking place during a single pressure application of the said die head.

From the foregoing description, taken in connection with the accompanying drawings, it is thought that the novel details of construction, the manner of use and the advantages of my invention will be readily apparent to those skilled in the art to which it relates.

What I claim is:

1. A heel seat preparing means comprising a head having a seat shaping concavity, and cutting edges positioned in part within and corelatively to the concavity so as to enable trimming and shaping of an out-sole end and seat shaping of said trimmed sole end and surrounding heel portions by a single pressure engagement of said head. 75

2. A heel seat preparing die head having a concavity to fit and pressure-shape heel seat portions to form a heel seat, and knife edges carried by the head within the concavity 80 shaped to suitably trim an out-sole extension for forming a central part of said heel seat.

3. A die head having a heel seat impressing concavity, and an out-sole extension cutting knife plate removably secured in said concavity and designed to sever surplus length from and shape an out-sole end and to cooperate with said concavity in forming a heel seat by a single pressure application on the said die head. 85

4. A heel seat preparing die head having a concavity to fit and pressure-shape heel seat portions to form a heel seat, and curved knife edges terminating in straight lateral extensions within the concavity shaped to suitably trim an out-sole extension for forming a central part of said heel seat. 90

5. A die head having a heel seat impressing concavity, and an out-sole extension cutting knife plate removably secured in said concavity, said knife plate having a U-shaped upstanding cutting edge terminating in lateral straight extensions and designed to sever surplus length from and shape an out-sole end and to cooperate with said concavity in forming a heel seat by a single pressure application on the die head. 100

6. A die head having a heel seat impressing concavity, and an out-sole extension cutting knife plate removably secured in said concavity, said knife plate having a U-shaped upstanding cutting edge terminating in lateral straight extensions and designed to sever surplus length from and shape an out-sole end and to cooperate with said concavity in forming a heel seat by a single pressure application on the die head, and said head having open lateral clearance recesses to receive the lateral knife end extensions and discharge the cuttings. 115

HARRY ZUBICK. 120
